UNITED STATES PATENT OFFICE.

NORBERT M. LA PORTE, OF BALTIMORE, MARYLAND, ASSIGNOR TO THE MOTOR COOLING SYSTEMS COMPANY, A CORPORATION OF MARYLAND.

CIRCULATING-EXHAUSTER.

1,183,302.

Specification of Letters Patent. Patented May 16, 1916.

Application filed April 20, 1915. Serial No. 22,649.

To all whom it may concern:

Be it known that I, NORBERT M. LA PORTE, a citizen of the United States of America, residing in the city of Baltimore, State of Maryland, have invented certain new and useful Improvements in Circulating-Exhausters, of which the following is a specification.

This invention relates to a circulating device for the cooling water used in connection with internal combustion engines to prevent overheating of the cylinder walls.

While this apparatus may be applied to the various types of engines, as marine and stationary, as well as those installed in road vehicles, it is illustrated as applied to an automobile engine. The circulator operates on a principle similar in some ways to that of the device described in my previous application for U. S. Patent Ser. No. 876,184, now pending. The principle of operation common to the two devices consists in leading a portion of the exhaust gases from the exhaust manifold to a nozzle in the circulating system which is disposed in the direction of circulation. In the previous application this has been shown in the lower radiator connection where it is submerged at all times even though the water content of the cooling system is diminished to a small fraction of the normal water supply. The exhaust gases escaping from the nozzle impart velocity to the water and serve most efficiently as a circulating medium, the effect of which varies to correspond to the heating effect. This device has been remarkably successful in its operation but objections to it have been raised in certain quarters on the ground that a portion of the grease and carbon from the exhaust is introduced into the cooling water and thus serves to foul the water jacket.

In order to avoid any possibility of fouling the cylinder jacket, I have provided a circulator so arranged that the exhaust gases, in so far as they are introduced into the cooling system, are released at a point near the surface of the water in the radiator and directed toward the surface so that any oil or carbon which is discharged floats up immediately and as the circulator in operation frequently raises the level of the water and causes a small quantity to overflow, the oil and carbon are thus thrown off without

being brought into contact with the radiator tubes or the inside of the cylinder jacket.

It has also been suggested that the introduction of hot exhaust gases into the circulator system would have an effect opposite to the cooling effect intended, but in the present instance, the gases escape almost immediately from the water into the air space in the top of the radiator from which they pass into the open air through the overflow pipe, and cannot have any appreciable effect in heating the water.

To accomplish the results described, I place a gas nozzle in the passage leading from the water jacket to the top of the radiator and turn the nozzle in the direction of the radiator. However, it is a well-known fact that owing to evaporation and leakage, the water level frequently recedes to a point well below the top connection and unless special provision is made for this condition, circulation will not be continued but will be interrupted whenever the level of the water recedes below the gas nozzle. To overcome this defect and produce a device which is operative at an increased range of water level, I reduce the diameter of the water pipe just beyond the nozzle so that the gas nozzle is directed into a sharply constricted area of the water pipe. The proportions of the circulator at this point are such that it is effective not only when supplied with water to the level of the nozzle, but it is also effective when the water falls below the nozzle to exhaust the air and produce a vacuum and suck the water up to the nozzle from whence it is forced into the top of the radiator, thus continuing the circulation even under wide variation of water level.

So much of an engine and radiator adapted for use on a road vehicle as is necessary to a complete comprehension of my device is shown in the accompanying drawings, in which—

Figure 1 is an elevation showing the circulator in longitudinal cross section; and Fig. 2 is a detail of the circulator.

Referring to the drawing by numerals; I have shown an engine casting 1 with the usual water jacket, a radiator 2, a connection 3 leading from the bottom of the water jacket to the bottom of the radiator, and a top connection 4. In the present instance I have substituted for the usual fittings and

hose at this point, a single tube having flanges 5 at the ends adapted to be bolted to the radiator at one end and to the cylinder casting 1 at the other end forming a connection between the top of the water jacket and the top of the cylinder. The top connection 4 is reduced in cross-section intermediate at 6 forming a constricted portion 7 into which the nozzle 8 is directed. This nozzle is connected by a small tube 9 with the exhaust manifold at 10 and has any suitable means, as a non-return ball valve 11, for preventing back flow of the water from the radiator to the manifold. In the preferred form of the invention, the constricted portion 7 of the radiator connection is made sufficiently small so that the action of the exhaust gases passing at high velocity from the nozzle through this constricted opening 7 will, in case the water level is below the radiator connection, entrain sufficient air to create a vacuum in the air space over the water and thus cause the water to rise to the level of the nozzle so that it will be forced through the constricted opening and upward, causing a continuous circulation in the system. It will be apparent that with the gases released at a point near the surface of the water in the radiator and in a current directed toward that surface, any carbon and oil which may be discharged will pass directly to the surface of the water and, being lighter than the water, will float. Further, the violent circulation produced in hill-climbing and the like, is sufficient at normal water level to raise the water and cause

a small amount to overflow. In this way all floating particles and scum are discharged before they have time to collect in appreciable quantities or become deposited on the radiator surface. Also the exhaust gases are not carried through the system to any extent but pass almost immediately to the surface of the water and out through the overflow pipe so that no heating from this source can possibly take place.

Having thus described my invention, what I claim and desire to secure by Letters Patent is:

An automobile accessory in the form of a circulating exhauster consisting of a tubular member to be used as a substitute for the radiator connection which extends from the top of the water jacket to the top of the radiator, the said tubular member having a constricted area forming a water nozzle disposed toward the radiator, a gas nozzle cooperating with and directed into the water nozzle, means connecting the gas nozzle to the exhaust manifold, the water nozzle and gas nozzle forming an ejector which carries the water from the water jacket to the radiator and entrains and forces the air through the radiator connection when the water level drops below normal, thus drawing the water up to the nozzle and forcing it forward to the radiator and continuing the circulation.

Signed by me at Baltimore, Maryland, this 16th day of April 1915.

NORBERT M. LA PORTE.
